UNITED STATES PATENT OFFICE.

JULIUS BOEKEL, OF PHILADELPHIA, PENNSYLVANIA.

ASPIRATOR.

No. 857,920.

Specification of Letters Patent.

Patented June 25, 1907.

Application filed November 22, 1906. Serial No. 344,664.

To all whom it may concern:

Be it known that I, JULIUS BOEKEL, a citizen of the United States, residing at Philadelphia, in the county of Philadelphia and State of Pennsylvania, have invented certain new and useful Improvements in Aspirators; and I do hereby declare the following to be a full, clear, and exact description of the invention, such as will enable others skilled in the art to which it appertains to make and use the same.

This invention relates to aspirators so called, which employ a current of water to draw air into the same, the air and water passing down together. The most common utility of such articles is to draw air from a reservoir below a liquid filter or to supply air and water to a reservoir, from the top of which the air may be drawn off to furnish pneumatic pressure. These articles, as commonly made and used, are composed of a water supplying pipe, an air-inlet pipe and an outlet pipe in line with said water pipe, the latter being so obstructed by a partition plate or its own undulating form as to break up the current of water and prevent the return of the air up the pipe, which would make the vacuum less complete and efficient.

The chief object of the present invention is to more perfectly draw in, and prevent such return of, the air. This I effect by giving the current of water a rotary motion before the current of air is drawn into it, which motion causes more perfect suction and continues after the air and water are mingled and is found practically to resist the ascent of the air more effectually than any solid impediment in the outlet pipe or any impeding form which may be given to it.

In the accompanying drawings, Figure 1 represents a side elevation of an aspirator embodying my invention. Fig. 2 represents a vertical longitudinal central section thereof; Fig. 3 represents a detail view of the spiral deflector which causes the rotary movement aforesaid.

A designates the tubular body of the aspirator having its upper end formed into an externally screw-threaded water inlet *a* connected by coupling *M* to any convenient source of water supply, as a pipe or a hydrant for example. B designates the outlet pipe extending vertically down from the lower end of said body. C designates the air inlet tube fitted into the side of said body and having a nipple *c* at its outer end adapted to receive

a rubber or other tube from a filter or other source of air-supply, or it may be used where a vacuum or light pressure of air is desired.

A longitudinal central bore *A'* extends from the interior of water inlet *a* to the outlet pipe *B* and is at its upper end of small diameter which remains unchanged for a short distance down, then widens a little forming an offset *h* above the air inlet & thereafter flares regularly downward to a equal diameter with said outlet pipe. A preferably downwardly inclined air passage *d* extends from a vacuum chamber *D* in the proximate part of air inlet pipe *C* to this bore *A'* just below the point where the flare therein begins. The outer end of said vacuum chamber communicates by a small passage *e* with a valve-chamber *f*, which may receive a check valve, though such valve is not necessary. A longer inlet bore *g* extends to the slotted end of said nipple and admits air to the aspirator.

A fixed spiral deflector *L* in water inlet *a* receives the downward current of water and gives it a spiral, rotary motion which continues during the passage of the water through the bore *A'* and outlet pipe *B*. The air drawn in through passage *d* circles downward with it and is prevented by the water, thus moving and expanding somewhat through such rotary motion, from ascending to the vacuum chamber and thus making the vacuum imperfect and lessening the power of such suction. In practice this device has been found exceedingly effective for that purpose, a recent test with the leading forms commonly in use, known as the Chapman and Richards aspirators, showing a gain of from about 35 per cent to about 500 per cent in time and a corresponding lessening of the amount of water needed to effect a given amount of work.

The outlet tube is just a straight plain cylindrical pipe with no need for any partition or special construction. The same is true of the water-inlet tube excepting the spiral deflector and the air inlet tube excepting the preferably downward inclination of passage *d*, which gives no trouble. The deflector for causing rotary motion is therefore the only real addition to the filter pump, which is very simple, and cheap to manufacture.

The water-inlet, the tubular-body of the aspirator and the outlet are in line and have no lateral openings except that for the air inlet, hence the water flows straight on, with only the forward spiral motion above de-

scribed, never turning back nor expanding laterally, but confined absolutely to a comparatively narrow passage. There is no need for any concentric or supplemental ele-

5 ments and consequently the device is cheap in manufacture, simple, solid, durable, unlikely to get out of order and is easily cleaned and repaired.

Having thus described my invention, what 10 I claim as new and desire to secure by Letters Patent is:

1. In an aspirator, a water inlet, a branch air-inlet and an outlet, in combination with a spiral deflector in said water inlet and a tubular body having said inlets and said outlet connected thereto, the said air inlet being connected to the bore of said body by a downwardly inclined passage, and the said bore being small and of equal diameter from the 15 said water inlet to the said passage, but flaring downwardly thereafter to the diameter of the outlet pipe which joins it substantially as set forth.

2. In an aspirator, a water inlet, a branch air-inlet and an outlet, in combination with a spiral deflector in said water inlet and a tubular body having said inlets and said outlet connected thereto, the longitudinal bore of 20 said body being small and of equal diameter from the water inlet nearly to the air-inlet but flaring downwardly thereafter to the diameter of the outlet pipe which joins it as set forth.

3. In an aspirator, a water outlet, a branch air-inlet and an outlet, in combination with 25 means in said water inlet for giving the current of water a rotary motion and a tubular body having said inlets and said outlet connected thereto, the longitudinal bore of said 30 body being small and of equal diameter from

the water inlet nearly to the air inlet, but flaring downwardly thereafter to the diameter of the outlet pipe which joins it substantially as set forth.

4. In an aspirator, a water inlet, a branch 45 air-inlet and an outlet, in combination with a spiral deflector in said water inlet and a tubular body to which said inlets and outlet are attached, the longitudinal bore of said body extending beyond the said inlets and both it 50 and the connected outlet being closed laterally, confining the aerated water to a single contracted channel substantially as set forth.

5. In an aspirator, a water-inlet, a branch air-inlet and an outlet in combination with a 55 device for causing rotary motion of the current of water arranged within the water inlet and a tubular body to which said inlets and outlet are attached, the longitudinal bore of said body extending beyond the said inlets 60 and both it and the connected outlet being closed laterally, confining the aerated water to a single contracted channel substantially as set forth.

6. In an aspirator, a water inlet, a tubular 65 body and an outlet arranged end to end with closed sides, confining the current of water to a direct contracted channel, in combination with an air inlet discharging into the bore of said body and a spiral deflector in said water 70 inlet, giving the current of water a rotary movement to prevent the return of the air substantially as set forth.

In testimony, whereof I have signed my name to this specification in the presence of 75 two subscribing witnesses.

JULIUS BOEKEL
